Jeny Corporation, Merchantville, N. J., a corporation of New Jersey

Application December 18, 1947, Serial No. 143,207

Term of patent 7 years

(Cl. D48—24)

To all whom it may concern:

Be it known that I, Joseph C. Clark, a citizen of the United States, residing in Merchantville, county of Camden, State of New Jersey, have invented a new, original, and ornamental Design for a Flashlight or the like, of which the following is a specification, reference being had to the accompanying drawing, forming part thereof.

In the drawing,

Fig. 1 is a side elevational view of a flashlight
or the like, showing my new design;

Fig. 2 is a bottom plan view thereof;

Fig. 3 is a top plan view thereof;

Fig. 4 is a front elevational view thereof; and

Fig. 5 is a rear elevational view thereof.

I claim:

The ornamental design for a flashlight or the like, as shown.

JOSEPH C. CLARK.
